(57) **CLAIM**

I claim the ornamental design for a bottle closure, as shown and described.

DESCRIPTION

FIG. 1 is a top perspective view of a first embodiment of the bottle closure in accordance with my new design;

FIG. 2 is a side view thereof;

FIG. 3 is a top plan view thereof;

FIG. 4 is a bottom view thereof;

FIG. 5 is a top perspective cross-sectional view taken in the direction of the line 5-5 shown in FIG. 3; and

FIG. 6 is a bottom, front perspective view thereof.

FIG. 7 is a top perspective view of a second embodiment of the bottle closure in accordance with my new design;

FIG. 8 is a side view thereof;

FIG. 9 is a top plan view thereof;

FIG. 10 is a bottom view thereof;

FIG. 11 is a top perspective cross-sectional view taken in the direction of the line 11-11 shown in FIG. 9; and,

FIG. 12 is a bottom, front perspective view thereof.

The dashed lines are for illustrative purposes only and forms no part of the claimed design.
